Arnold M. PLAISTED.

UNITED STATES PATENT OFFICE.

HAROLD M. PLAISTED, OF ST. LOUIS, MISSOURI, ASSIGNOR TO WILLIAMS PATENT CRUSHER & PULVERIZER COMPANY, OF ST. LOUIS, MISSOURI, A CORPORATION OF MISSOURI.

ROTARY PIVOTED HAMMER.

Application filed March 15, 1923. Serial No. 625,309.

To all whom it may concern:

Be it known that I, HAROLD M. PLAISTED, a citizen of the United States, residing at St. Louis, State of Missouri, have invented 5 certain new and useful Improvements in Rotary Pivoted Hammers, of which the following is a specification.

This invention relates to certain new and useful improvements in rotary pivoted hammers for shredders and other reducing machines, the peculiarities of which will be hereinafter fully described and claimed. 10

The main object of my invention is to provide a reversible three-pronged insert piece 15 for a rotary pivoted hammer adapted to be mounted in multiple in a rotor and enclosing casing of a reducing machine, and especially adapted for shredding alfalfa, herbage and like material; secondly, to prolong 20 the life of said hammer by providing three points in succession brought to operative position as they wear out in use.

In the accompanying drawing on which like reference numerals indicate corresponding parts, Fig. 1 represents a side face view of a hammer exemplifying my invention, with hammer support and cage indicated by dotted lines; Fig. 2, a front edge view of the same; Fig. 3, a side face view of the insert 30 piece alone; and Fig. 4, an edge view of said piece for a relatively thin shank.

1 designates a flat bar shank having a hole 2 for pivotal mounting on a rod in a disc mounted in multiple on a rotor shaft 35 the axis of which, designated 3, is parallel to the axis 4 on which the said hammer is pivoted. The shank is preferably relatively thin as shown in Fig. 2, such as $\frac{1}{16}$ " thick by $2\frac{1}{2}$ " width, and in the front outer corner 40 of the head of said shank is formed a recess 5 of such shape as to receive an insert piece 6 which is mounted therein. This insert piece has three prongs 7 which are equidistant from the center and from each other. 45 Each prong has a front edge surface 8 that is curved from the point inward towards the center, and then outward to form the back 9 of the next prong, till it intersects the outer edge 10 that is inclined inward 50 towards the center to give clearance to the point 11. Each prong is thus tapering and is symmetrical with the others, so that each may be inserted in the corresponding recess 5 of the hammer head which tapers to the 55 rear from the front edge 12 of the shank,

and follows the curve of the insert piece so that one point 11 of the insert piece is disposed at the front edge 12 of the shank, while another outer point 11 is located considerably in front of the front edge of the shank in the operative position shown in Fig. 1, thus presenting the curved side edge 8 to the material being reduced. The edge surface 10 of the point in operative position is continued by the end surface 13 of the 60 head end of the shank, giving clearance between the cage and the hammer as indicated by the broken curved line 14 struck from the pivot center axis 4. The general direction of the hammers and rotor is indicated 65 by the arrow 15.

Suitable fastening means are provided for the insert piece, such as rivets 16 passing through matching notches 17 and 18 formed respectively in the edge surface of the recess 75 and the edge surface of the insert piece, and preferably countersunk as indicated. These notches in the insert piece are located on a circle 19 Fig. 3, from the center of the said piece, so that each prong in succession may 80 be brought to rearward position in the recess and be secured by rivets through the openings formed by the matching notches. As shown in Fig. 1, the two rivets holding the tapering prong prevent said prong from 85 leaving the recess, while the rivets near the outer and inner prongs maintain the respective prongs in the plane of the shank as shown in Fig. 2. The tapering shape of each prong and the location of the prongs 90 as shown in Fig. 1, provide a design of hammer that is especially effective in reducing alfalfa, herbage, and like material.

I claim:

1. A rotary pivoted hammer comprising 95 a shank adapted for pivotal mounting and having a recess in the front outer corner, a symmetrical three-prong insert piece mounted in said recess so that one prong projects forward of the front edge of the shank in operative position, and means for detachably securing said piece in said recess.

2. A rotary pivoted hammer comprising a shank adapted for pivotal mounting and having a recess at its front outer corner, a symmetrical three-pronged insert piece mounted in said recess so that one prong projects forward of the front edge of the shank in operative position, another prong 100 is disposed adjacent to the front edge of the 105 shank in operative position, and another prong 110

shank and the third prong extends to the rear into said recess, and fastening means detachably securing said piece in said recess.

5 3. A rotary pivoted hammer comprising a shank adapted for pivotal mounting and having a recess at its front outer corner, a symmetrical reversible three-pronged insert piece mounted in said recess,—each prong 10 tapering to an acute cutting point forming operative edges successively disposed in operative position, and having notches matching corresponding notches on said recess forming openings to receive fastening rivets,—and fastening means mounted in said 15

openings and detachable means for securing said insert piece, substantially as described.

4. In a rotary pivoted hammer, a reversible insert piece consisting of three symmetrically disposed prongs having acute points 20 equidistant from the center and adapted to form three successive operative edges,—said prongs having notches for fastening rivets located equidistant from the center of the piece on the side edges of said prongs, substantially as and for the purpose described.

25 In testimony whereof I have affixed my signature.

HAROLD M. PLAISTED.
